LIFT JACK

Ted M. Parker, Kansas City, Mo.

Application June 3, 1948, Serial No. 30,825

3 Claims. (Cl. 254—8)

1

My invention relates to a lift jack and more particularly to a hand lift jack that is portable and adapted to employ a suitable means, such as a screw or hydraulic jack, for raising and lowering the lift arm or boom thereof for lifting loads such as motors or other objects as in a garage, shop or manufacturing plant, one end of an automobile or the like, and depending upon the size and capacity thereof, up to 2500 pounds or more.

An object is to provide a portable lift jack having a frame with a base supported on wheels, including steering wheels on a turn table or fifth wheel with a handle to pull or push it around from place to place where it is to be used so as to be properly and accurately positioned relative to the load or object to be lifted.

Another object is to provide a lift jack having a wheeled carriage, frame or base with an upright member or mast thereon at one end, preferably the steering end, and an overhanging arm or boom hinged or pivoted to the top of the frame and so correlated thereto as to extend over the frame or base to engage an object to be lifted, this arrangement precluding the possibility of the jack tipping over and means, such as a hydraulic or screw jack between the frame and vertically movable or swingable lifting arm or boom to raise or lower the latter and thus an object connected to or arranged above or beneath the arm or boom.

Another object is to so construct the lifting arm or boom that same is permanent while the length thereof may be extended, an extension boom, arm, part or element being provided for this purpose having means correlative with the boom to detachably fix the extension element to the arm so that it will be rigid therewith when used or readily detached or removed from the permanent lifting arm or boom whereby the latter or shorter normal length may be used as dictated by the lifting job at hand.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings,

Figure 1 is a top plan view of a lifting jack embodying my invention,

Figure 2 is a side view of the lifting jack,

Figure 3 is an end view thereof,

2

Figure 4 is an enlarged detailed fragmentary vertical sectional view showing the mounting of the turn table or fifth wheel for steering the portable wheeled frame or base of the lifting jack,

5 Figure 5 is a fragmentary detail plan view showing the extension boom associated in correlative position to the lifting arm or boom for use as in Figure 2.

Referring to the drawings, the lift jack embodies a substantially horizontal wheeled carriage, frame or base 10 of substantially U-shape having sides 14, a transverse closed front end or bight portion and the opposite or rear end open and the rear ends of sides 11 provided with bearing forks 12. The frame may be constructed of suitable bar metal such as flat stock, angle iron, or otherwise and the sides 11 are connected at points spaced from the open rear end and forks 12, as through the medium of an inverted angle bar 13 welded or otherwise attached at its ends to said sides. The extremities of the sides or legs 11 are provided with upwardly converging side plates 14, all parts where connected being welded or otherwise fastened together. The upper ends of the side members or plates 14 have portions 15 substantially parallel to each other and provided with holes to receive a horizontal shaft or transverse pivot 16 which may be solid or a pipe. The sides 11 at the bottom portions 20 of the side members or plates 14 are also connected by a transverse bar 17 which may be in the form of a channel as shown, or otherwise, so as to effectively brace the frame at this end and preferably adjacent the top edges of the side members 11.

35 The members 14 form a mast and pivoted to the shaft 16, at one end, is a vertically swinging arm or boom 18 having converging sides 19 forming an isosceles triangle centered over the fifth wheel 41 with the apex thereof extending toward the front of the frame 10 with apertured parallel end portions 20 receiving the shaft in connection with the upper end portions 15 of the side members 14, the shaft being held by suitable retaining means on its ends indicated as cotter pins 21. Also, the portions 20 are preferably disposed in contact with the inner sides of the portions 15 and converge toward their free ends and the free end of the arm or boom 18 where they are secured together as at 22, by welding or otherwise. Near their free ends, the sides 19 are in contact and provided with top recesses 23 forming a hook over which a chain or other element may be disposed for raising and supporting a load. A cross brace 24 connects the

converging sides 19 near the pivot end of the arm or boom.

The base is further strengthened by angular reinforcing or gusset plates 25 welded along the top edges of the sides 11 and the lower portions of the front edges of the side members or plates 14 of the mast, the sides 14 preferably sloping beyond the adjacent end of the base as indicated, particularly in Figure 2 of the drawings, and the adjacent end portions of the reinforcing plates, webs or gussets 25 being similarly inclined and tapered as shown so as to somewhat conform to the inclined edges of the sides 14. In addition, oppositely inclined or diagonal braces 26 are extended between the sides 14 and the cross brace 17 and at their upper ends, support a horizontal plate or table 27 which is connected at its ends to the sides 14 at an elevated point, as by welding and has a forwardly extending tapered portion on which a transverse tubular member or pipe 28 is arranged to support a plate 29 having an angle iron rim 30 within which a screw or hydraulic jack 31 is mounted. The jack is adapted to be operated by a crank 32 and has movable plunger 33 and a head 34 with a transverse tubular or pipe bearing member 35 to engage beneath the cross brace or plate 24 whereby upon operating the hand jack, the arm or boom 18 may be raised or lowered to raise or lower a load attached to the free end of the free end thereof.

At the open rear end, the forks 12 of the frame are each provided with a short transverse axle 36 shown as located outwardly of sides 11 of the jack frame or truck 10 with bars attached at the outside of bars 11 to form the forks 12 therewith, and the axles 36 held in bearing boxes 37 to take wheels 38 so that the jack frame or truck can straddle a load or be backed up to a bench to set the load down conveniently or with no trouble. Wheels 38 are shown as having suitable anti-friction bearings 39, if desired, and axles 36 are held in position as by suitable retaining means such as cotter pins 40. At the opposite end, the cross brace or channel 17 bears on a turn table or fifth wheel 41 comprising longitudinal parallel short bars 42 disposed on edge and parallel to each other and also welded equidistantly on either side of the center of length of the cross brace 17 at the bottom thereof. A disc or circular plate 43 is secured to the bars 42 and bears on a similar disc or plate 44, while a kingpin or center pivot 45 extends centrally through the discs and an axle 46 at this narrow end of the frame, which as shown is preferably formed of an inverted channel-shaped member of considerably shorter length than the frame but provided with reduced spindle ends 47 to take wheels 48 constituting the steering wheels of the device and equipped, if desired, with similar bearings 39 and held in position by cotter pins 40 the same as described in connection with the rear axles and wheels. These wheels 48 are positioned at a spaced distance inwardly from the sides of the frame as clearly shown in Figure 3 of the drawings and the outer edge of the axle is provided with apertured pivot ears or lugs 49 to which a fork 50 at the inner end of a handle bar 51 is pivoted horizontally to swing up and down as indicated at 52. The fork 50 comprises bars of metal anchored on each side of the handle bar 51 at parallel portions 53 by welding or otherwise at their converging ends and the free end of the handle bar is provided with a cross bar or handle 54.

Means is provided for extending the length of the arm or boom 18 and for this purpose, an extension arm or boom 55 is provided, this part or

element comprising spaced bars 56 bent toward each other at common ends as indicated at 57 and welded or otherwise anchored together as indicated at 58 and formed with recesses 59 in their top edges to provide a hook similar to the end of the arm 18. The spaced portions 56 are connected by a lower cross member or bolt 60 near their inner ends and lower edges and by a similar bolt 61 spaced therefrom near their top edges, so that the extension part or element may be slipped over the free end of the arm 18 with the bolt 60 extending under the ends 22 and the bolt 61 seating in the recess 23 to hold the extension arm or boom rigid to give greater length and leverage.

It will thus be seen that I have provided a portable, hand lift jack in which the vertically swingable arm or boom extends over the wheeled frame or base from one end and in this way will support the load to be raised or lowered without tipping over. This is also facilitated and the extension of the base from the mast and the boom or arm thereover increased, to enlarge the distance that the device may be projected over an object to be raised by having the boom or arm pivoted over one end of the base or wheeled frame and also because of the rearwardly inclined or sloping position of the mast relative thereto. For instance, the wheeled base or frame may be extended beneath an automobile and the arm or boom projected into a car or over a motor to lift the transmission or motor as it is thought will be obvious. Other large loads may be correspondingly lifted by operation of the jack disposed in spaced relation but adjacent to the pivoted end of the arm or boom, so as to make the device especially useful in a garage, shop or manufacturing plant for lifting various loads. Also, by reason of the handle and turn table at one end of the wheeled frame or base and the steering wheels pivoted as described, the steering of the device is facilitated and the jack may be accurately and properly positioned relative to the load in addition to being conveniently pulled or pushed around from place to place where it is to be used.

I claim:

1. A portable lift jack comprising a wheeled base frame having axles and wheels including steering wheels at one end of the frame, a handle bar connected to the steering wheel axle, said latter axle having a fifth wheel connection to the frame, a mast including side bars attached to the frame at points disposed outwardly of and to each side of said fifth wheel sloping inwardly and upwardly with ends thereof terminating beyond the end of the frame to form fixed spaced ends disposed above and rearwardly of said fifth wheel, an arm having spaced sides pivoted to the upper ends of the side bars of the mast for vertical swinging movement and overhanging the frame, and a horizontal support carried by the mast having side bars formed with divergent ends secured to the frame.

2. A portable lift jack comprising a wheeled base frame having axles and wheels including steering wheels at one end of the frame, a handle bar connected to the steering wheel axle, said latter axle having a fifth wheel connection to the frame, a mast including side bars supported by the frame and having sloping upper ends extending beyond the end of the frame, an arm having sides pivoted to the upper ends of the side bars of the mast for vertical swinging movement and overhanging the frame, a horizontal support disposed under said arm having divergent vertical

side bars carried by the frame, the sides of the arm being spaced and secured in contact toward their free ends and having a top recess formed transversely thereof, and lift means pivotally carried by and having a movable head engageable with the support and bottom of the arm to raise the latter.

3. A wheeled hoist comprising a base frame having a pair of spaced side members joined at ends thereof by a cross member to form a closed rear end portion with opposite ends of said side members being extended to form a pair of free ends spaced from said cross member forming an open front end, spur shafts extending outwardly of said front end at right angles thereto, wheel means mounted on said spur shafts, a fifth wheel mount carried by said cross member at the rear end of the frame with spaced wheels carried by said mount movable about the axis thereof for steering, a mast carried by said frame having spaced side plates extending upwardly and rearwardly from each of said side members of the frame with terminating ends thereof spaced apart above and to the rear of said base frame, a transverse bar extending between said terminating ends, a lift boom formed with a pair of converging side members pivotally mounted on said

transverse bar with the converging ends thereof extended and joined together for vertical movement above the front end of said frame, the spaced portion of said boom members forming an isosceles triangle disposed above said fifth wheel, a support carried by said mast having spaced uprights extending from said side members, and pivoted lift means carried by said support disposed under said boom.
